US0D1036314S

(12) **United States Design Patent** (10) Patent No.: **US D1,036,314 S**
(45) Date of Patent: ** Jul. 23, 2024

(54) **UPPER FRAME FOR AN OFF-ROAD VEHICLE**

(71) Applicant: **Polaris Industries Inc.**, Medina, MN (US)

(72) Inventors: **Akshay A Biyani**, Minnetonka, MN (US); **Ian M. Dunn**, Chanhassen, MN (US); **Dennis Lutz**, Blaine, MN (US); **Charles J. Olson**, Andover, MN (US); **Alex M. Baltes**, Wayzata, MN (US)

(73) Assignee: **Polaris Industries Inc.**, Medina, MN (US)

(**) Term: **15 Years**

(21) Appl. No.: **29/845,622**

(22) Filed: **Jul. 8, 2022**

(57) **CLAIM**

We claim the ornamental design for an upper frame for an off-road vehicle, as shown and described.

DESCRIPTION

FIG. 1 is a left front perspective view of an upper frame for an off-road vehicle of the present application;

FIG. 2 is a left side view of the upper frame of FIG. 1;

FIG. 3 is a right side view of the upper frame of FIG. 1;

FIG. 4 is a top view of the upper frame of FIG. 1;

FIG. 5 is a bottom view of the upper frame of FIG. 1;

FIG. 6 is a front view of the upper frame of FIG. 1; and,

FIG. 7 is a rear view of the upper frame of FIG. 1.

The portions of the upper frame for the off-road vehicle shown in broken lines form no part of the claimed design.

1 Claim, 7 Drawing Sheets
